UNITED STATES PATENT OFFICE.

HUGH W. SANFORD, OF KNOXVILLE, TENNESSEE.

RAILWAY CAR.

Application filed December 3, 1923. Serial No. 678,310.

My improvement relates particularly to mine cars which are to be turned or tilted bodily for the discharge of the contents of the car.

One object of my invention is to produce a mine car which is adapted to be turned or tilted for the discharge of its contents, as above stated, and which has its floor or bottom low relative to the track, in order that, for a given head room, the car will hold a maximum load, and, for the sake of greater stability of the car on the track, carry the load close to the track rails.

A further object of the invention is to produce a car which possesses flexibility allowing partial twisting of the car frame to permit one axle of the car to incline out of the horizontal plane of the other axle, in order that all the wheels of the car may at all times bear fully upon the track rails, notwithstanding irregularities in the height of the rails. In this connection it is to be remembered that the axles of many cars of this type are not swiveled but rest in bearings which are fixed on the car body or frame; and in this connection it is further to be remembered that in mining practice the track rails are usually not level nor well supported, a large part of the trackage being temporary and constructed and maintained with the least labor. And it is also to be noted that whenever one wheel of such a car does not rest well on the track, that car is apt to leave the track and thus wreck itself and the train of which it forms a part. Hence such adaptability through frame flexing is of definite practical importance.

To these ends, the car, in its preferred form, includes strong end sills and strong side sills and two axles and a floor, the side sills having their ends joined to the end sills and said four sills forming a frame which is flexible and yet of ample strength for resisting all strains, including the weight of the load, end thrust, and longitudinal train pulls, and the axles being combined with the side sills above the bottom of said sills, and the major part of the floor being below the level of the axles and the floor being so supported as to allow the car frame formed by the end sills and side sills such flexibility as will permit the twisting of the frame to allow the wheels to remain in engagement with the track rails, although there are

irregularities in the track, as above mentioned.

The major feature of the supporting of the floor is the attachment of the ends of the floor to the end sills while the side edges of the floor are left free or substantially free from the side sills. A secondary feature of such supporting consists in forming such relation between the floor and the axles of the car as to cause parts of the floor to be supported by the axles.

In the accompanying drawings,

Fig. 1 is a side elevation of a car embodying my invention, parts being broken away;

Fig. 2 is a plan of the same car, parts being broken away;

Fig. 3 is a longitudinal, middle, upright section of the car of Figs. 1 and 2;

Fig. 4 is a similar section, the car bottom being in another form;

Fig. 5 is a transverse, upright section on the line 5—5, of Fig. 3, looking toward the left;

Fig. 6 is an upright transverse section on the line, 6—6, of Fig. 4, looking toward the right;

Fig. 7 is a horizontal section on the line, 7—7, of Fig. 3;

Fig. 8 is a horizontal section on the line, 8—8, of Fig. 3;

Fig. 9 is an upright, transverse section on the line, 9—9, of Fig. 3, looking toward the right;

Fig. 10 is an upright section on the line, 10—10, of Fig. 3;

Fig. 11 is an upright sectional detail showing a U-bolt used for supporting the floor or bottom plate.

Referring first to Figs. 1, 2, 3, 5, 7, 8, 9 and 10, the drawings, A, A represent end sills each having a bumper A¹, projecting outward therefrom and said sills having a draw bar element, A², also projecting outward from the end sills and located over the bumper, and the end sills comprising trusses, A³, corner stiffeners, A⁴, and gusset stiffeners, A⁵, all preferably formed of one integral casting.

The aforesaid bumper, A¹, is swelled outward as indicated by the drawing, and immediately over the central portion of the bumper is the aforesaid draw bar element, A², provided with a coupling pin opening, A⁶, which is directly over a similar open-

ing, A⁷, of the bumper, a space being left between the draw bar element, A², and the bumper, A¹, for the reception of a coupling link, the coupling pin being designed to drop through the openings, A⁶ and A⁷.

The corner stiffeners, A⁴, which have been described as being part of the integral casting are to be securely riveted to the longitudinal or side sills, B, the sills being slotted 10 as shown at B¹ to afford space for the gusset stiffeners, A⁵.

The side sills, B, are to be so heavy as to make them amply strong to resist downward strain or drooping and to resist end-15 wise thrust and also train pull. At the same time, the frame consisting of the side sills and the end sills must possess sufficient flexibility to allow the axles to incline independently of each other, whereby the car 20 wheels at the same side of the car are allowed to assume different levels to conform to variations or irregularities in level of the track on which the car runs.

The two axles, C, are arranged trans-25 versely to the side sills and rest in bearings, C¹, secured to the side sills by bolts, C². In the form shown in the drawings, said bearings extend through the side sills and comprise a plate bolted flatwise to the outer 30 sides of the side sills. On each end of each axle is a track wheel, C³. This arrangement brings the axles above the level of the lower edges of the side sills.

A single floor or bottom plate, D, of heavy 35 sheet or plate metal extends from one end sill, A, to the other and from one side sill, B, to the other and has its ends up-turned to form upright end flanges, D¹, each of which bears against the inner face of the adjacent 40 end sill and is joined thereto by rivets, D². The side edges of the floor plate are turned upward to form upward-directed flanges, D³, each of which over-laps the lower part 45 of the inner face of the adjacent side sill. But said flanges are not joined to the frame. Only the ends of the bottom plate are secured to the frame.

The bottom plate is supported on the end sills, as above described, and also from the 50 axles, C, and bearings, C¹. For this latter purpose inverted V-form hanger straps, D⁴, extend across the axles, C, and across the bearings, C¹, and have their ends resting on and joined to the bottom plate by means of 55 rivets, D⁵. These straps hold the bottom plate against downward movement. To prevent upward movement, a bridge plate, D⁶, is placed within each strap horizontally and close to the axle, the ends of the bridge plate 60 being secured to the straps by rivets, D⁷. A sleeve, D⁸, surrounds each axle at its middle and forms a support for the middle strap, D⁴.

In Fig. 4 the bottom plate is divided into 65 three parts or sections, D, the sections meet-

ing under the axles, C, and having their meeting edges up-turned to form upward-directed flanges, D⁹, which are so near each other as to substantially prevent leakage of coal or other material hauled in the car. The 70 V-form hangers and the bridge plates are applied in this form the same as they are applied in the form shown by Fig. 3, and the attachment to the end sills is the same as in Fig. 3, and the side edges are flanged upward as in Fig. 3.

As a substitute for the hanger straps, D⁴, a U-bolt, E², is extended over the axles or bearings and through the floor plate and through a washer plate, E³. Nuts, E⁴, are placed on the ends of the arms of the U-bolt below and against the washer plate.

The axles, C, and the bearings, C¹, and the sleeves, D⁸, are so related to each other 85 that they may be regarded as together forming axle structures, those structures constituting intermediate supporting or hanging means for the car bottom.

From the foregoing it will be seen that in these several forms the ends of the bottoms 90 are secured to the frame ends and that the side edges of the bottom are free from the frame sides. Thus the frame formed by the side sills and the end sills is to the least extent restrained from flexing or twisting to 95 allow all the four wheels of the car to bear fully upon the track rails, whereby danger of derailing the car is reduced to a minimum.

In all these forms, the upward-directed 100 side flanges, D³, of the bottom serve to prevent leakage of coal along the lower edges of the side sills.

When built in any of the forms shown by the drawings, this car is well adapted to be turned sidewise for the discharge of its load. 105 At many mines, such turning is done by means of a rotary tipple.

From the foregoing description it will be seen that further variations of the structure may be made, the structure yet comprising a 110 car frame having ends and sides and the structure comprising further a bottom or floor secured to the frame ends and free from the frame sides, whereby the frame sides are allowed the largest degree of freedom for 115 flexibility.

I claim as my invention:—

1. In a car of the kind described, the combination of a frame, axles transverse to the 120 length of the frame and located above the lower edges of the frame sides, a plate bottom having its ends secured to the frame ends and said bottom extending approximately to the level of the lower edges of the frame sides and substantially free from said sides, whereby the frame is given freedom for flexing or twisting, substantially as described.

2. In a car of the kind described, the combination of a frame, axles transverse to the 130

- length of the frame and located above the lower edges of the frame sides, a plate bottom having its ends turned upward and secured to the frame ends and said bottom extending approximately to the level of the lower edges of the frame sides and substantially free from said sides, whereby the frame is given freedom for flexing or twisting, substantially as described.
- 5 3. In a car of the kind described, the combination of a frame, axles transverse to the length of the frame and located above the lower edges of the frame sides, a plate bottom having its ends secured to the frame ends and said bottom having its side edges turned upward and said bottom extending approximately to the level of the lower edges of the frame sides and substantially free from said sides, whereby the frame is given freedom for flexing or twisting, substantially as described.
- 10 4. In a car of the kind described, the combination of a frame, axles transverse to the length of the frame and located above the lower edges of the frame sides, a plate bottom having its sides and ends turned upward and having its ends secured to the frame ends and said bottom extending approximately to the level of the lower edges of the frame sides and substantially free from said sides, whereby the frame is given freedom for flexing or twisting, substantially as described.
- 15 5. In a car of the kind described, the combination of a frame, axles transverse to the length of the frame and supporting the frame sides, a plate bottom having its ends secured to the frame ends and said bottom being axle-supported intermediate its ends and the side edges of said bottom being substantially free from the frame sides, whereby the frame is given freedom for flexing or twisting, substantially as described.
- 20 6. In a car of the kind described, the combination of a frame, axles transverse to the length of the frame and located above the lower edges of the frame sides, a plate bottom having its ends secured to the frame ends and said bottom being axle-supported intermediate its ends and the side edges of said bottom being substantially free from the frame sides, whereby the frame is given freedom for flexing or twisting, substantially as described.
- 25 7. In a car of the kind described, the combination of a frame, axles transverse to the length of the frame and located above the lower edges of the frame sides, a plate bottom having its ends secured to the frame ends and said bottom being axle-supported intermediate its ends and the side edges of said bottom being substantially free from the frame sides, whereby the frame is given freedom for flexing or twisting, substantially as described.
- 30 8. In a car of the kind described, the combination of a frame, axles transverse to the length of the frame and located above the lower edges of the frame sides, a plate bottom having its ends secured to the frame ends and said bottom being axle-supported intermediate its ends and the side edges of said bottom being substantially free from the frame sides, whereby the frame is given freedom for flexing or twisting, substantially as described.
- 35 9. In a car of the kind described, the combination of a frame, axles transverse to the length of the frame and located above the lower edges of the frame sides, a plate bottom having its ends secured to the frame ends and said bottom having up-turned edges and having its ends secured to the frame ends and said bottom being axle-supported intermediate its ends and the side edges of said bottom being substantially free from the frame sides, whereby the frame is given freedom for flexing or twisting, substantially as described.
- 40 10. In a car of the kind described, the combination of a frame, axles transverse to the length of the frame and located above the lower edges of the frame sides, a plate bottom having its ends secured to the frame ends and said bottom being axle-supported intermediate its ends and the side edges of said bottom being substantially free from the frame sides, whereby the frame is given freedom for flexing or twisting, substantially as described.
- 45 11. In a car of the kind described, the combination of a frame, axles transverse to the length of the frame and located above the lower edges of the frame sides, a plate bottom having its ends secured to the frame ends and said bottom extending approximately to the level of the lower edges of the frame sides and substantially free from said sides and axle-supported intermediate its ends, whereby the frame is given freedom for flexing or twisting, substantially as described.
- 50 12. In a car of the kind described, the combination of a frame, axles transverse to the length of the frame and located above the lower edges of the frame sides, a plate bottom having its ends secured to the frame ends and said bottom extending approximately to the level of the lower edges of the frame sides and substantially free from said sides and having up-turned side edges and being axle-supported intermediate its ends, whereby the frame is given freedom for flexing or twisting, substantially as described.
- 55 13. In a car of the kind described, the combination of a frame, axles transverse to the length of the frame, bearings secured to the frame sides and extending outward of said sides and surrounding the axles be-

- tween the frame sides, a plate bottom having its ends secured to the frame ends and being at approximately the level of the lower edges of the frame sides and substantially free from said sides, and supporting members engaging a part of said bearings and the bottom, whereby the frame is given freedom for flexing or twisting, substantially as described. 5
- 10 14. In a car of the kind described, the combination of a frame, axles transverse to the length of the frame and located above the lower edges of the frame sides, bearings secured to the frame sides and surrounding the axles between the frame sides, a plate bottom having its ends secured to the frame ends and being at approximately the level of the lower edges of the frame sides and substantially free from said sides, and supporting members engaging a part of said bearings and the bottom, whereby the frame is given freedom for flexing or twisting, substantially as described. 15
- 20 15. In a car of the kind described, the combination of a frame, axles transverse to the length of the frame, bearings supported by the frame sides and surrounding the axles between the frame sides, a plate bottom having its ends secured to the frame ends and being at approximately the level of the lower edges of the frame sides and substantially free from said sides, and hangers and bridge pieces engaging a part of said bearings and the bottom, whereby the frame is given freedom for flexing or twisting, substantially as described. 25
- 30 16. In a car of the kind described, the combination of a frame, axles transverse to the length of the frame and located above the lower edges of the frame sides, bearings supported by the frame sides and surrounding the axles between the frame sides, a plate bottom having its ends secured to the frame ends and being at approximately the level of the lower edges of the frame sides and substantially free from said sides, and hangers and bridge pieces engaging a part of said bearings and the bottom, whereby the frame is given freedom for flexing or twisting, substantially as described. 35
- 40 17. In a car of the kind described, the combination of a frame, axles transverse to the length of the frame and supporting the frame sides, a single plate bottom having its ends secured to the frame ends and the side edges of said bottom being substantially free from the frame sides, whereby the frame is given freedom for flexing or twisting, substantially as described. 45
- 50 18. In a car of the kind described, the combination of a frame, axles transverse to the length of the frame and supporting the frame sides, a single plate bottom having its ends secured to the frame ends and said bottom being axle-supported intermediate its ends and the side edges of said bottom being substantially free from the frame sides, whereby the frame is given freedom for flexing or twisting, substantially as described. 55
- 60 19. In a car of the kind described, the combination of a frame, axles transverse to the length of the frame and supporting the frame sides, a single plate bottom extending below the axles and having its ends secured to the frame ends and the side edges of said bottom being substantially free from the frame sides, whereby the frame is given freedom for flexing or twisting, substantially as described. 65
- 70 20. In a car of the kind described, the combination of a frame, axles transverse to the length of the frame and supporting the frame sides, a single plate bottom having up-turned edges extending below the axles and having its ends secured to the frame ends and the side edges of said bottom being substantially free from the frame sides, whereby the frame is given freedom for flexing or twisting, substantially as described. 75
- 80 21. In a car of the kind described, the combination of a frame, axles transverse to the length of the frame and supporting the frame sides, a single plate bottom extending under the axles and having its ends secured to the frame ends and said bottom being axle-supported intermediate its ends and the side edges of said bottom being substantially free from the frame sides, whereby the frame is given freedom for flexing or twisting, substantially as described. 85
- 90 100 In testimony whereof I have signed my name, this 28th day of November, in the year one thousand nine hundred and twenty-three. 105

HUGH W. SANFORD.
